UNITED STATES PATENT OFFICE

169,153

WASHING MACHINE

Norman S. McEwen, Fort Lauderdale, Fla.

Application April 16, 1952, Serial No. 19,348

Term of patent 3½ years

(Cl. D49—1)

To all whom it may concern:

Be it known that I, Norman S. McEwen, a citizen of the United States, residing at Fort Lauderdale, county of Broward, State of Florida, have invented a new, original, and ornamental Design for a Washing Machine, of which the following is a specification, reference being had to the accompanying drawing forming a part hereof.

The figure is a perspective view of a washing machine showing my new design. The rear of the washing machine is plain and unornamented.

I claim:

The ornamental design for a washing machine, as shown and described.

NORMAN S. McEWEN.
